CLOTHESLINE SUPPORT

Frank J. Hencir, St. Paul, Minn.

Application March 12, 1945, Serial No. 582,354

1 Claim. (Cl. 211—119.15)

1

My invention relates to an improvement in clothes line support wherein it is desired to provide a clothes line which may be easily strung up or taken down.

It is ordinarily disadvantageous to leave clothes lines up during all types of weather. The clothes line becomes damp in wet weather and collects dust and soot thereupon. This dust and soot is often transmitted to the clean clothes, creating a very undesirable situation. Clothes lines also often become loosened or lengthened somewhat under strain and a fixed clothes line must accordingly be tightened somewhat from time to time, which is rather difficult to do when the lines are tied tightly at the ends thereof.

It is the object of the present invention to provide a clothes line arrangement by means of which the clothes line may be kept in a closed container when not in use and by means of which the clothes line may be easily put up and tightened. With my clothes line arrangement it is extremely easy to tighten the line and this tightening operation may be accomplished before the clothes are hung thereupon or afterwards if it is so desired. As a result the clothes may be placed upon the clothes line while the lines thereof are rather slack if it is so desired and the clothes line may then be tightened to avoid danger of any of the clothes supported thereby from contacting the ground.

A feature of the present invention resides in the provision of a winding reel upon which the clothes line may be wound which is enclosed within a housing having a removable closure. When this removable closure is in closed position the clothes line will be entirely protected from the elements. When the closure is open the clothes line may extend therefrom and may be strung between the clothes line supports. A ratchet apparatus is provided for holding the clothes line taut when erected.

A feature of the present invention lies in a simple means of anchoring the free end of the line. I provide a block having a pair of holes therethrough through which the clothes line may be inserted to provide a loop between the holes. The end of the line is threaded between this loop and the surface of the block so as to tightly anchor the end of the line.

A further feature of the present invention lies in the provision of a clothes line supporting structure which may be easily applied to a conventional clothes pole or the like. My clothes line support includes a pair of elongated bars which are secured in parallel relation to the cross arms

2

of a clothes pole of any conventional type. These elongated arms are provided with pulleys mounted thereupon over which the line may be readily threaded. The elongated strips bearing the pulleys, together with the clothes line box or housing for enclosing the line when the same is not in use may be sold as a unit for application to clothes posts which have been previously erected. A feature of the present invention resides in the fact that the pulleys are supported above the strip in such a way that the line may be easily threaded over the same without the necessity of inserting the line through numerous pulley apertures or the like.

An added feature of the invention resides in the pulley arrangement for guiding the line into the box or housing. One of the pulleys or one of the elongated strips is off-set relative to the others to guide the line toward a pulley mounting upon the cross arm posts above the line housing. As a result the line may be fed to the clothes line reel from a single direction.

These and other objects and novel features of my invention will be more clearly and fully set forth in the following specification and claim.

In the drawings forming a part of my specification the figure illustrates, in perspective, a pair of clothes line posts having my clothes line support attached thereto.

30 My clothes line support is designed for attachment to a conventional type of clothes line post having a cross arm mounted thereupon. The clothes line post 10 is supported in the ground or attached to any fixed support and is designed to extend vertically. A cross arm 11 is secured to the top of the post 10 to extend on either side thereof. The post 10 and cross arm 11 form a T-shaped support. A post 12 similar to the post 10 extends vertically at any desired distance from the post 10. The post 12 is likewise provided with a cross arm 13 similar to the cross arm 11. The cross arms 11 and 13 are arranged in substantially parallel relationship.

An elongated strip 14 is secured to the top of the cross arm 11 by any suitable means, such as by bolts or cap screws 15. The strip 14 rests upon the cross arm 11 and is supported thereby. Pivotal supports such as bolts or cap screws 16, 17, 18, and 20 act to support clothes line pulleys 21, 22, 23, and 24, respectively. These pulleys are rotatably mounted on the strip 14 and may turn freely on their respective pivots. The various pulleys may be equally spaced or not, as is desired.

55 At one end of the strip 14, I provide a block 25

or an upstanding flange on the strip 14. The block 25 is secured to the strip by bolts or cap screws 26. A pair of parallel apertures 27, and 29 are provided through the block. These apertures are substantially horizontal and are directed toward the corresponding end of the opposing cross arm 13.

A second strip 30 is secured to the cross arm 13 by any suitable means such as by bolts or cap screws 31. Bolts or pivots 32, 33, 34 and 35 are supported by the strip 30 and act as pivotal supports for a series of pulleys 36, 37, 39 and 40, respectively. These pulleys are freely rotatable about their substantially vertical axes.

An arm 41 which is off-set at 42 acts as a support for a pulley 43. The pulley 43 is provided with a substantially vertical bolt or pivot 44 extending into or through the arm 41. Thus the pulley 43 is forwardly of the remaining pulleys 36, 37, 39 and 40 supported by the strip 31, and is also somewhat below the level of these remaining pulleys.

The pulley 24 is arranged in substantially opposed relation to the pulley 43. The pulleys 19 and 40 are in opposed relation. The pulley 22 is opposed to the pulley 39. Similarly the pulley 21 is in opposed relation to the pulley 37 on the strip 30. The remaining pulley 36 on this same strip 30 is in opposed relation to the aperture 27 of the block 25.

A pulley 45 is secured by a horizontally extending bolt or pivot 46 to the post 12. Directly below the pulley 45 upon the post 12 I provide a housing illustrated in general by the numeral 47. This housing is arranged to enclose the clothes line when it is not in use. The housing or enclosure 47 is box-shaped and is provided with a closed bottom 49, opposed side walls 50, and 51 secured thereto, and opposed front and rear walls 52 and 53 respectively. The various side walls and the base form an open topped container or housing within which the clothes line may be reeled. A top or cover 54 is hinged along one edge 55 to the rear wall 53. When the cover 54 is in the elevated position shown, the clothes line housing is open and the clothes line 56 may extend therefrom. When the clothes line is taken down it is entirely enclosed within the housing and the cover 54 closes the open top of the receptacle.

A shaft 57 is supported by the side walls 50 and 51 of the housing and may support a spool or reel if it is so desired. A ratchet gear 59 is normally engaged by a dog or pawl 60 to hold the reel from unwinding. A crank arm 61 provided with a gear handle 62 provides a means of rotating the shaft 57. The end of the line 56 is anchored to the shaft 57 in any suitable way such as by extending through an aperture in the shaft. It is essential that the end of the line 56 is held from rotation relative to the shaft 57.

When it is desired to erect the clothes line the cover 54 of the housing 47 is opened and the end of the line 56 is extended over the pulley 45 and subsequently over the pulleys 43, 24, 23, 40, 39, 22, 21, 37, and 36. The end of the line is extended through the aperture 27, and then through the second aperture 29 in the opposite direction. The extreme end 63 of the line is then threaded between the loop 64 between the apertures 27 and 29 and the block 25. When a pull is exerted upon

the line the loop 64 tightens, firmly locking the end 63 of the line from accidental disengagement.

After the line has been engaged over all of the various pulleys and the end 63 of the line has been locked in the manner described the line is tightened by means of the crank 61. Obviously during the engagement of the line over the various pulleys, the dog or pawl 60 is disengaged from the ratchet so that the line may unreel therefrom. When the line is tightened, however, the pawl 60 is again engaged with the ratchet 59 to hold the line taut.

Obviously the line may be left slack until the clothes are placed thereupon and later tightened. Similarly the line may be tightened in the event it should be found to sag somewhat at any time whether or not clothes are being supported thereby.

The reverse operation to that previously described enables the line to be taken down. When the end of the line has been removed from its anchor the line may be wound upon the shaft 57 until it is entirely within the container 47, at which time the cover 54 may be closed.

In accordance with the patent statutes, I have described the principles of construction and operation of my clothes line support and while I have endeavored to set forth the best embodiment thereof, I desire to have it understood that obvious changes may be made within the scope of the following claim without departing from the spirit of my invention.

I claim:

A clothes line support for use in combination with T-shaped clothes poles comprising a pair of relatively thin, flat, elongated strips, means at spaced intervals securing said strips in parallel relation to the cross arms of the T-shaped poles to be reinforced thereby, spaced pulleys mounted for rotation upon said strips, means on one end of one of said strips to which the end of the line may be anchored, a downwardly extending flange on the forward edge of the other of said strips at one end thereof, a horizontally extending flange projecting forwardly from the lower end of said downwardly extending flange, a pulley supported upon said horizontally extending flange, a pulley on the post of the T-shaped pole to which said other strip is attached, a shaft mounted on said one pole below said pulley, a ratchet on said shaft, a pawl on said one pole adjacent said ratchet and engageable therewith to prevent rotation thereof in one direction, and a crank on said shaft for rotating the same.
